UNITED STATES PATENT OFFICE

163,795

SAFETY RAZOR HOLDER

Nikki Eastman, Port Chester, N. Y.

Application February 24, 1948, Serial No. 144,670

Term of patent 3½ years

(Cl. D4—3)

To all whom it may concern:

Be it known that I, Nikki Eastman, a citizen of the United States, residing at 2 Rye Road, Port Chester, in the county of Westchester, State of New York, have invented a new, original, and ornamental Design for Safety Razor Holder, of which the following is a specification, reference being had to the accompanying drawing, constituting a part hereof.

Fig. 1 is a perspective view of a safety razor holder, showing my new design.

Fig. 2 is a top plan view.

Fig. 3 is a front elevational view.

Fig. 4 is a side elevational view.

I claim:

The ornamental design for a safety razor holder, substantially as shown.

NIKKI EASTMAN.
